TRANSMISSION

Palmer Orr, Muncie, Ind., assignor to Borg-Warner Corporation, Chicago, Ill., a corporation of Illinois

Application June 22, 1942, Serial No. 447,902

10 Claims. (Cl. 192—3)

This invention relates to motor vehicle transmissions of the type in which the ignition of the vehicle engine is interrupted in order to relieve the torque load on interengaging drive control elements which are adapted when engaged to establish a drive of one ratio, and, when disengaged, to permit a drive of a different ratio to be established through the transmission. In transmissions of this type, it is customary to employ a manual switch, preferably operated by the engine throttle, for forcing down the drive from one ratio to another, the interruption of the ignition circuit being effected simultaneously with the energization of an electromagnetic device for controlling the engagement and disengagement of the drive control elements. Such electromagnetic device is customarily in the form of a solenoid incorporating an ignition restoring switch made operative by the disengagement of the drive control elements. It is customary to employ relays in the ignition circuit and in the solenoid energizing circuit. In the present practice, interruption of the ignition is effected by short circuiting the same. This may be designated a "closed" circuit system.

One of the characteristics of such a "closed" circuit system is that there is a drain on the battery during each ignition interruption, which is heavier than the normal load imposed by the ignition mechanism. This not only creates a burden upon the battery but also deteriorates the circuit breakers of the ignition system.

The primary object of the present invention is to provide an open circuit system in which the ignition circuit is interrupted by opening the same instead of by shorting the same, and to provide such a circuit with a minimum of change in the control system now in use in overdrive transmissions. Particularly it is aimed to employ the same solenoid construction including the ignition restoring switch.

In general, this is accomplished by providing an arrangement in which there is provided an ignition restoring circuit, controlled by a solenoid operated switch and parallel with an ignition destroying circuit of the open circuit type. A particular object of the invention is to provide an arrangement of this kind wherein the solenoid controlled switch is located directly in the ignition restoring circuit, eliminating relays in this immediate circuit.

A further object of the invention is to provide a circuit of the type indicated, wherein provision is made for a sufficient interval of delay between the operation of the manual switch which con-

trols the forcing down of the drive, and the opening of the ignition circuit, to permit the removal of any coast load that may be imposed upon the drive control elements, prior to the interruption of the ignition.

A more specific object of the invention is to provide a transmission control circuit in which automatic means is provided for establishing a drive of one ratio and in which there is provided manual means for shifting the drive from that ratio back to another ratio, in the form of a delayed opening relay having one set of contacts adapted, when separated, to deenergize the solenoid and having another set of contacts adapted, when separated, to open one of two parallel ignition circuits, the other of which at the time is standing open at a switch that is adapted to be closed by the disengagement of the drive control element, whereby to restore the ignition.

Other objects, the advantages and uses of the invention will become more apparent after reading the following specification and claims, and after consideration of the drawings forming a part of the specification wherein:

Fig. 1 is a schematic view of the control mechanism of an overdrive transmission embodying the invention, the parts being shown in overdrive position;

Fig. 2 is a similar view with the parts shown in direct position.

As an example of one form in which the invention may be embodied, I have shown in the drawing the control mechanism of an overdrive transmission in which the mechanical parts, i. e., the planetary gearing, clutches, sun gear braking mechanism, and governor are constructed and arranged as shown in Fig. 1 of the pending application of Harold E. Carnagua, Serial No. 309,718, filed December 18, 1939.

Such an overdrive transmission, which is well known and extensively used, includes planetary gearing which is adapted, when the sun gear thereof is braked, to transmit an overdrive from the input to the output shaft, and an overrunning clutch which is adapted to pick up the drive in direct ratio when the drive through the planetary gearing is released by freeing the sun gear for rotation.

The sun gear braking mechanism includes a slotted locking ring which is attached to the sun gear. This slotted ring is shown in the drawing at 42 and cooperates with a pawl 47 which is adapted to engage in one of a number of slots 43 in the periphery thereof so as to lock the sun gear against rotation. A solenoid, indicated gen-

erally at 61, is adapted, when energized, to urge the pawl 47 toward engagement with the annular member 42. Such engagement is prevented, as long as the sun gear is rotating, by a balk ring 50 which has a slipping clutch connection with the sun gear and thus tends to rotate with the locking ring 42. When the pawl 47 is thus biased the engagement may be completed by throttling down the engine, thus placing a coast load on the planetary gearing and causing the sun gear, which has previously been rotating, along with the rest of the planetary gearing, in unison with the driven shaft, to slow down and finally to commence rotating in reverse. This reversal of rotation will carry the balk ring 50 to a position wherein the pawl 47 may pass through an opening 53 in the balk ring, into one of the slots 43 of the locking ring.

The pawl 47 is connected to the armature 71 of the solenoid 61 by means of a rod 65 which is slidably received in a longitudinal bore in the armature and receives pawl projecting thrust from the armature through the medium of a coil spring 83 engaged between a flange 70 on the rod 65 and a cap 75 on the end of the armature. When the solenoid is energized, the armature 71 is drawn toward the pawl 47, compressing the spring 83, which, when the balk ring 50 permits the pawl 47 to advance, pushes the pawl 47 into one of the slots 43.

The solenoid 61 includes a moving coil 80 and a holding coil 81 both of which are energized for biasing the pawl toward braking position, the coil 80 being deenergized when the pawl 47 goes into the slot 43 and the coil 81 remaining energized for holding the pawl in the slot. The deenergization of the coil 80 is accomplished by a self-closing switch including contacts 85 and 86, the latter being carried by an arm 87 which is disposed so as to be engaged by a flange 76 on the cap 75 as the armature advances.

When the circuit through the holding coil 81 is broken, the armature is retracted by a spring 77 engaged between the flange 76 and an abutment 78 in the solenoid casing.

The foregoing structure all forms part of the conventional overdrive transmission disclosed in the pending application Serial No. 309,718 referred to above. Such a conventional overdrive transmission also includes the motor ignition 142, the conventional battery 91 which energizes the solenoid 61 as well as the ignition 142, the ignition switch 143, and a rail switch 107 which functions to open the solenoid circuit when the conventional manually shifted transmission of a motor vehicle is shifted to reverse drive. In the conventional arrangement there is provided a shunt circuit by means of which the ignition is shunted out.

The conventional control arrangement also includes a governor 98 for speed responsive energization of the solenoid, and a manual control device for opening the solenoid circuit when the governor 98 is in circuit-closing position, thereby to permit the transmission to be forced back into direct drive when operating in the overdrive range of speed. This manual control customarily includes, in series with the governor 98, a manual switch including contacts 104 bridged by a connector 105 mounted on a push rod 106 which is adapted to be operated by the engine accelerator pedal. It is also customary to employ a relay having contacts forming part of the solenoid energizing circuit and other contacts forming part of an ignition control circuit, and in

addition a delayed action relay for restoring the ignition in the event the normal restoring means fails to function.

The present invention, in addition to securing the desired advantage of interrupting the ignition by opening the circuit thereof instead of shorting it, utilizes a simpler relay mechanism than the conventional relay mechanism referred to above, and at the same time guards against the failure of ignition restoration. To this end, I provide an ignition restoring circuit which is open when the sun gear locking pawl is engaged and an ignition interrupting circuit, in parallel with the restoring circuit, adapted to be opened by a delayed action relay which also serves to open the solenoid circuit, thus temporarily leaving both circuits open. The delayed opening of the relay permits the engine to speed up when the accelerator controlled "kick-down" switch is actuated for deenergizing the relay, thereby removing, prior to ignition interruption, any coast load that may be imposed on the drive control elements.

The ignition interrupting circuit includes, in series in the order named, the battery 91, a conductor 200, the ignition switch 143, a conductor 200a, an ignition interrupting switch 201, a conductor 202, and the ignition 142.

The switch 201 constitutes one pair of contacts of a delayed action relay 203 including an energizing coil 204 and a second pair of contacts 205, the latter being disposed in the solenoid energizing circuit. One of each pair of contacts 201 and 205 is mounted on an arm 206 spring biased as at 207 toward open position. Energization of the coil 204 causes the contacts 201 and 205 to close. Opening of the circuit by which the coil 204 is energized causes the latter to become slowly deenergized, resulting in the delayed opening of the contacts 201 and 205.

The ignition restoring circuit includes, in the order named, the battery 91, the conductor 200, the ignition switch 143, a conductor 208, an ignition restoring switch including contacts 135 and 136, a conductor 209, and the ignition 142.

The ignition restoring switch is of a self-opening type, the contact 136 being carried by an arm 137 which is biased toward switch opening position as indicated by the schematic representation of a spring 138. Ignition is restored as a result of the engagement of the arm 137 by an extension of the rod 65, when the pawl 47 is retracted.

The primary control circuit for energizing the relay coil 204, includes, in the order named, the current source 91, a conductor 210, the coil 204, a conductor 211, the manual switch 104, 105 and the governor 98.

The solenoid energizing circuit includes, in the order named, the current source 91, a conductor 117, the contacts 205, a conductor 212, the rail switch 107, a conductor 213, and the parallel solenoid coil circuits 81 and 80, 85, 86.

In overdrive operation, the parts are in the position shown in Fig. 1. With the transmission set for forward drive the rail switch 107 will be closed. Upon operation above the overdrive cut-in speed, the governor 98 will close the primary control circuit, energizing the coil 204 and causing the contacts 201 and 205 to close. The closing of the contacts 205 establishes the solenoid energizing circuit, causing the pawl 47 to be projected into engagement with the balk ring 50. Simultaneously with the closing of the solenoid energizing switch 205, the ignition interrupting switch 75

201 will close to establish the ignition interrupting circuit through which the ignition is energized as long as the transmission operates in overdrive. A reversal of torque on the sun gear, effected by relaxing the accelerator pedal, will result in the balk ring 50 moving to a non-blocking position, permitting the pawl 47 to enter the notch 43 in the sun gear locking ring 42. The advancing movement of the pawl rod 65, which has previously held the switch 135, 136 in closed position, permits the latter to open under the pull of the spring 138, thus opening the ignition restoring circuit. The ignition now will be maintained through the ignition interrupting circuit as previously described.

With the parts in the overdrive position, and without a reduction in speed such as to open the governor 98, the transmission may be restored to direct drive by opening the manual switch 104, 105. This is accomplished by depressing the accelerator pedal. Opening the switch 104, 105 causes the gradual deenergization of the coil 204 and, after a short interval of delay, the opening of the switches 205 and 201. During this interval of delay the engine may accelerate under the increased depression of the accelerator pedal, so as to remove any coast load that may be imposed upon the sun gear. Should the switch 201 be opened while a coast load was imposed on the sun gear there would be no reversal of torque on the sun gear such as to free the pawl 47 from the notch 43.

The interruption of the ignition while the sun gear is under normal forward drive load causes a momentary reversal of torque which releases the pawl 47 and permits the spring 77 to retract the armature 71 relative to the now deenergized coils 80 and 81. The retrograde movement of the pawl rod 65 closes the switch 135, 136 and reestablishes the ignition through the ignition restoring circuit.

The invention provides a simplified control circuit of a type in which the ignition is interrupted by open circuiting the same. The ignition restoring switch 135, 136 is directly included in one of the parallel ignition circuits, without a relay. The other ignition circuit is controlled by a switch which opens and closes simultaneously with the solenoid energizing switch, and may therefore be mounted on a common armature therewith.

While I have described my invention in connection with one specific embodiment thereof, it is to be understood that this is by way of illustration and not by way of limitation and the scope of my invention is defined solely by the appended claims which should be construed as broadly as the prior art will permit.

I claim:

1. Control mechanism for a multiple drive ratio transmission of a motor vehicle including an engine having ignition means; said control mechanism comprising positively interengageable drive control elements adapted when disengaged to permit the transmission to operate in one drive ratio and when engaged to establish another drive ratio, said elements being subject to torque loads when engaged and being freely disengageable only when said loads are relieved, electromagnetic means adapted when energized to urge one of said elements in one direction of its movement, yielding means to urge said one element in the opposite direction, means for establishing an energizing circuit through said electromagnetic means, a relay including a pair of contacts adapted to form a part of said energizing circuit, means for establishing two circuits in parallel through said igni-

tion means for energizing the same, one of said parallel circuits including a switch controlled in accordance with the position of said drive control elements and adapted to be opened when said elements are engaged, and the other of said parallel circuits including a pair of contacts forming parts of said relay and adapted to open in unison with said electromagnetic means energizing contacts while said first mentioned parallel circuit stands open, and to thereby open circuit the ignition upon deenergization of the electromagnetic means.

2. Control mechanism as defined in claim 1, wherein said switch is adapted to be closed upon disengagement of said drive control elements, so as to restore the ignition.

3. Control mechanism as defined in claim 1, wherein said relay has a delayed opening action, whereby to permit the engine to accelerate to remove coast loads from said interengaging elements prior to interruption of the ignition.

4. Control mechanism for a multiple drive ratio transmission of a motor vehicle including an engine having ignition means; said control mechanism comprising positively interengageable drive control elements adapted when disengaged to permit the transmission to operate in one drive ratio and when engaged to establish another drive ratio, said elements being subject to torque loads when engaged and being freely disengageable only when said loads are relieved, electromagnetic means adapted when energized to urge one of said elements in one direction of its movement, yielding means to urge said one element in the opposite direction, means for establishing an energizing circuit through said electromagnetic means, a relay including a pair of contacts adapted to form a part of said energizing circuit, means for establishing two circuits in parallel through said igni-

tion means for energizing the same, one of said parallel circuits including a switch controlled in accordance with the position of said drive control elements and adapted to open when said elements become engaged and the other of said parallel circuits including a pair of contacts forming part of said relay and adapted to open in unison with said electromagnetic means energizing contacts while said first mentioned parallel circuits stands open, and to thereby open circuit the ignition upon deenergization of the electromagnetic means, said switch being adapted to be closed upon disengagement of said drive control elements, so as to restore the ignition, and primary control means for controlling the operation of said relay.

5. Control mechanism as defined in claim 4, wherein said primary control means include an accelerator controlled switch adapted to effect deenergization of the electromagnetic means in unison with engine acceleration, and wherein said relay has a delayed opening action to permit said engine acceleration to remove coast loads from said drive control elements prior to interruption of the ignition.

6. Transmission control mechanism for a motor vehicle having an engine including ignition means, and having a transmission of a type comprising relatively fast speed driving means including positively interengageable drive control elements adapted to establish a drive therethrough when engaged, said elements being subject to torque loads when engaged, and being freely disengageable only when said loads are relieved, and relatively slow speed driving means including a device automatically operable to establish a drive there-

through in response to the release of the fast speed

driving means; said control mechanism comprising electromagnetic means adapted when energized to urge one of said elements in one direction of its movement, yielding means urging said one element in the other direction of its movement, means for establishing an energizing circuit through said electromagnetic means, and means for establishing two circuits in parallel through said ignition means for energizing the same, one of said circuits including a switch adapted to be opened when the drive control elements are engaged and to be closed by disengagement of said elements, and a relay including a first set of contacts forming a portion of said energizing circuit for the electromagnetic means and a second pair of contacts forming part of the other of said parallel ignition circuits, the last mentioned contacts being adapted to be opened in unison with the deenergization of the electromagnetic means, whereby to open the second of said parallel circuits and interrupt the ignition.

7. Control mechanism for an overdrive transmission of a motor vehicle having an ignition system, planetary gearing including a sun gear adapted to be braked to establish an overdrive through said planetary gearing, direct drive means adapted to automatically establish a direct drive when said sun gear is released for rotation, and positively interengageable elements adapted when engaged to brake said sun gear, said control mechanism comprising electromagnetic means for biasing one of said elements in one direction of its movement, yielding means for biasing said one element in the other direction of its movement, means for establishing an energizing circuit through said electromagnetic means, a relay including a first set of contacts forming part of said energizing circuit, and means for establishing two parallel circuits through said ignition means, including a self-opening switch forming part of one of said circuits and adapted to be closed by disengagement of said elements and including a second pair of contacts in said relay forming part of the other of said parallel circuits

and adapted to be opened upon deenergization of the relay, whereby to interrupt the ignition and relieve the torque load on said drive control element.

5 8. In a control mechanism as defined in claim 1, primary control means for controlling the operation of said relay, including a governor and a manually operated switch in series therewith.

9. In a control mechanism as defined in claim 1, 10 primary control means for controlling the operation of said relay, including speed responsive and accelerator operated switches in series therewith, said relay having a delayed opening action permitting the engine to accelerate in unison with the

15 actuation of said accelerator operated switch, sufficiently to remove coast loads on said drive control elements prior to the interruption of the ignition.

10. Control mechanism for an overdrive transmission of a motor vehicle having an ignition system, and having planetary gearing of a type including a sun gear adapted to be braked to establish an overdrive through said planetary gearing, direct drive means adapted to automatically establish a direct drive when said sun gear is released for rotation, and a pawl for braking said sun gear; said control mechanism comprising a solenoid adapted when energized to urge said pawl toward braking position, resilient means for retracting said pawl when the solenoid is deenergized, means for establishing an energizing circuit through said solenoid, a relay including a pair of contacts forming part of said energizing circuit, and means establishing two circuits to 35 said ignition means, one of said circuits including a self-closing switch adapted to be closed by retraction of said pawl and the other of said two circuits including a second pair of contacts in said relay which are adapted to be opened upon deenergization of the solenoid, thereby to interrupt the ignition and relieve the torque on the sun gear.

PALMER ORR.
